UNITED STATES PATENT OFFICE.

MALCOLM CURRY, OF SCARSDALE, NEW YORK, ASSIGNOR TO THE AMERICAN THREAD COMPANY, OF NEW YORK, N. Y., A CORPORATION OF NEW JERSEY.

WOUND BOBBIN.

Application filed February 3, 1926. Serial No. 85,670.

My invention relates to wound bobbins and has for its object to provide a new and improved wound bobbin comprising a core, a mass of thread wound thereon, and end pieces applied subsequently to the winding of the mass.

With the paper ended bobbins now in use, experience has shown that there is at times a tendency for an opening to appear between the end of the mass and the edge of the applied disks into which the thread may slip so as to catch. This liability is partly due to the change of the form of the end surface of the mass during the pressing operation, and to the tendency of these end surfaces to return to their original shape. In my improved bobbins I avoid this by retaining substantially the end shapes as originally wound and making the end pieces conform approximately thereto.

In those earlier bobbins also the end of the tube makes frictional contact with the end walls of the bobbin holders, tending to hold the outer faces of the end pieces out of engagement with those walls, and thus concentrating the retarding friction more particularly at surfaces which are of comparatively small diameter and liable to be somewhat uneven. I have found it of advantage to have the frictional contact occur at points more remote from the axis, i. e., at points approximately midway between the core and the outer edges of the disks. This provides a more efficient friction and a smoother friction surface.

The objects of my invention are to attain these results.

The following is a description of my invention, reference being had to the accompanying drawings, in which,

Fig. 1 shows my improved bobbin at one stage of its manufacture;

Fig. 2 shows a cross-section of a complete bobbin embodying my invention; and

Fig. 3 shows an end view of the same.

Referring more particularly to the drawings, 2 is a tubular core made of paper or other suitable material upon which is wound a mass of thread 4, the wind being the well known "universal" wind. This mass is wound so that its end surfaces between the core and periphery bulge slightly as at 6. 8 are perforated end disks of cardboard or

other suitable material which are, before application, pressed so as to have the concavo-convex form shown in Fig. 1, i. e., so that the portion between the perforation and the edge of the disk bulges outwardly, the concavo-convex surface engaging and conforming more or less to the outward bulges on the ends of the mass. The portion of each disk, in the zone immediately adjacent to the perforation, is preferably flat, as shown at 10, and before application the curvature of the bulge in the disk adjacent to the periphery thereof as at 12 is slightly sharper than the corresponding bulge on the end of the mass, with the result that when the disks are forced downward so as to contact with the end of the mass, as shown in Fig. 2, they are placed under a spring tension which holds the same in close contact with the periphery of the adjacent end surface of the mass.

In forming the bobbin of Fig. 2 the parts are assembled as in Fig. 1, with a mass of thread 4' universally wound on the core 2', and pressure is then applied to the disks forcing them into close contact with the mass, and preferably slightly compressing the mass, whereupon the ends of the core 80 are turned over as shown at 14, holding the parts together.

The bulging of the end pieces provides a central re-entrant portion 15 lying within the highest elevation 16 of the end disks so that the turned over ends of the core are within the central recesses, with the result that the contact between the bobbin holder and the ends of the bobbin is at the highest point 16, resulting in a friction drag at 90 that distance from the center. The turned over ends of the core are thus held out of engagement with the bobbin holder.

With the mass so wound and the disks so pre-formed and applied, not only is the frictional contact between the wound bobbin and the bobbin holder at a point removed from the core, but if the mass for any reason expands axially, it tends to expand uniformly and the ends, as well as the disks, tend to retain the original curvatures of the completed product, so that the disks, such expanding notwithstanding, are held in contact with the outer peripheries of the end surfaces of the mass, thus preventing the formation of any 105 opening such as hereinbefore referred to.

The smaller normal radius of curvature of the formed disks co-operates in producing this result by causing the disks to have a spring tension, assisting in maintaining such engagement.

I preferably use for the disk a heavy paper or cardboard, such as is commonly used for tags and the like, but obviously other materials having similar forming and spring-like qualities may be used. For commercial purposes I prefer the heavy paper on account of its low cost, and also on account of the efficient friction surfaces provided.

I prefer to secure the end pieces by crimping over the ends of the core as described, but my invention is not limited to this means of holding the end pieces.

As will be evident to those skilled in the art, my invention permits of various modifications without departing from the spirit thereof or the scope of the appended claims.

What I claim is:

1. In a wound bobbin the improvement which consists in a mass of thread wound upon a tubular core and having end surfaces between the core and its periphery protruding beyond the portions adjacent to the core and the periphery, and disks having annular concave surfaces engaging said protruding surfaces, the disks being secured to said core and held adjacent to said mass.

2. In a wound bobbin the improvement which consists in a mass of thread wound upon a tubular core and having end surfaces between the core and its periphery protruding beyond the portions adjacent to the core and the periphery, and disks having annular concavo-convex surfaces, the concave surfaces engaging said protruding surfaces, the disks being secured to said core and held adjacent to said mass, the disk tending to assume a shape in which the radial curve of its concave surface is slightly

sharper than the radial curve of the end surfaces engaged thereby.

3. In a wound bobbin the improvement which consists in a mass of thread wound upon a tubular core and having a protruding end surface between the core and its periphery and disks having annular concavo-convex surfaces, the concave surfaces engaging said protruding surfaces, the disks being secured to said core and held adjacent to said mass, said disks having central re-entrant portions within which the ends of the core are contained.

4: In a wound bobbin the improvement which consists in a mass of thread wound upon a tubular core and having a protruding end surface between the core and its periphery, and disks having annular concavo-convex surfaces, the concave surfaces engaging said protruding surfaces, the disks being secured to said core and held adjacent to said mass, said disks having re-entrant portions within which the ends of the core are contained, said disks having flattened zones adjacent to the core.

5. In a wound bobbin the improvement which consists in a mass of thread wound upon a tubular core and having end surfaces between the core and its periphery protruding beyond the portions adjacent to the core and the periphery, and disks having annular concave surfaces engaging said protruding surfaces, the disks being secured to said core and held adjacent to said mass, and curved externally so that a plane surface resting on the outer portion of either disk contacts therewith only at points radially spaced away from said core and said periphery.

In testimony whereof, I have signed my name to this specification this first day of February, 1926.

MALCOLM CURRY.
